PLAQUE

Bert Rodney Anderson, Golf Road,
Reading, Pa. 19601

Filed Mar. 7, 1969, Ser. No. 16,115

Term of patent 14 years

Int. Cl. D11—02

U.S. Cl. D29—23

FIG. 1 is a front elevation of a plaque showing my new design; and,

FIG. 2 is a side elevation thereof.

The broken lines are shown for illustrative purposes only and form no part of the claimed design.

I claim:

The ornamental design for a plaque, as shown and described.
